UNITED STATES PATENT OFFICE.

CHARLES W. LAWSER OF BALA, PENNSYLVANIA, ASSIGNOR TO WICACO SCREW & MACHINE WORKS, INC., OF PHILADELPHIA, PENNSYLVANIA, A CORPORATION OF PENNSYLVANIA.

SPINNING PUMP.

Application filed December 29, 1926. Serial No. 157,784.

This invention relates to improvements in pumps of the type used in the manufacture of artificial silk for forcing the viscous base substance through the spinnerets.

It is customary in the type of pump to which this invention particularly relates to pivotally mount the pump in a bracket or base by means of hollow nipples or arms which engage the pump casing at and register with the intake and exhaust ports respectively, the nipples or arms functioning both to pivotally support and to conduct the viscous base substance to and from the pump. It is the principal object of the present invention to provide a novel construction of pump casing whereby the pressure applied to the pump casing when clamped in the bracket will not distort the pump cylinder.

In the attached drawings:

Figure 1 is a side view of a pump made in accordance with my invention;
Fig. 2 is an end elevation;
Fig. 3 is a rear end elevation of the pump, and
Fig. 4 is a partial longitudinal sectional view on the line 4—4, Fig. 1.

Referring to the drawings, the pump comprises a cylinder casing 1 in which is mounted a rotor 2. A cylindrical extension 3 of the rotor 2 projects through an opening in the cylinder head 4 and has attached thereto a gear 5 by means of which the rotor 2 may be rotated in the cylinder. In the present instance, the gear 5 is a spiral gear and is adapted, when mounted as hereinafter described, to mesh with a worm 6 on a drive shaft 7. The rotor 2 has in the present instance a pair of longitudinal cylindrical bores 8 and 9 which have at their inner ends transverse channels or ports, 11 and 12 respectively, opening into the sides of the piston, and these ports are adapted as herein-after described to communicate with suitably arranged intake and discharge ports in the cylinder casing 1. The pump further comprises a pair of plungers 13 and 14 which reciprocate in the cylinders 8 and 9, and which are actuated through the medium of a cam or the like (not shown) in the casing. The form of the plunger actuating means may vary widely, as well understood in the art, and forms no part of the present invention.

In the walls of the casing are formed, in

the present instance, a pair of circumferentially arranged channels, 15 and 16, which respectively extend around slightly less than half of the circumference of the cylinder. As shown in Figs. 1, 2 and 3, the casing 1 is formed with a transverse boss or enlargement 17 at one side, and in this enlargement 17 and at opposite sides of the casing are formed an intake port 18 and a discharge port 19, these ports communicating respectively with the channels 15 and 16 through passages 21 and 22. It will now be seen that as the rotor 2 is rotated in the cylinder, the cylinders 8 and 9 are connected, through a part of each revolution with the intake port 18, and for another part, with the discharge port 19. The movement of the plungers 13 and 14 are timed with respect to the rotation of the rotor 2 and the positions of the grooves 15 and 16 so that during the period in which the respective cylinders 8 and 9 are connected with the intake port 18, the plungers are being retracted or withdrawn from the cylinders, whereas during the period that the cylinders are connected with the discharge port 19, the pistons are advancing in the cylinders.

It is customary to mount pumps of this type pivotally through the medium of hollow nipples connected respectively with the source of supply of the viscous substance from which the artificial silk is formed and with the spinnerets through which the substance is extruded in thread-like formation, the nipples engaging the casing respectively at the intake and discharge ports. The hollow nipples are shown in Figs. 1 to 3, inclusive, and are designated by the reference numerals 23 and 24.

It will be noted that the pivotal axis of the casing through these nipples is parallel with the axis of the worm shaft 7. With this arrangement, and by reason of the natural tendency of the worm and spiral gear to separate, excessive pressure occurring within the pump results in the casing tilting upwardly at the front around the said pivotal axis until the gear 5 and worm 6 are disengaged. To maintain the operative relation between the gear 5 and the worm 6 under normal conditions, it is necessary to securely clamp the casing between the nipples 23 and 24. It has been customary in the past to design the casing so that the intake and dis-

charge ports are on opposite sides of the cylinder in which the rotor 2 rotates, and under these circumstances pressure exerted between the nipples may and frequently does 5 result in a distortion of the cylinder with a consequent loss of efficiency in the pump, undue wearing of the parts, and defective operation seriously affecting production. In the present instance, it will be noted that the 10 pivotal axis between the nipples 23 and 24 is eccentrically arranged with respect to the cylinder to an extent positively preventing distortion of the cylinder regardless of the pressure that may be applied to the casing 15 between the nipples. In other words, by forming the casing 1 with the offset part 17 in which the ports 18 and 19 are formed, I provide a practically solid abutment extending between the ports capable of withstanding 20 any pressure that may be applied to the casing in the bracket, without adversely affecting the pump.

I claim:

1. A spinning pump comprising a casing 25 having a cylindrical chamber and a solid transverse portion offset laterally with respect to the axis of said chamber and having at opposite sides thereof ports communicating with the chamber, means for clamping 30 the cylinder pivotally between elements respectively engaging the casing at said ports, said clamping elements having passages communicating with said ports whereby the connection between the ports and the 35 passages is maintained regardless of the angular position of the casing with respect to the pivotal axis, a rotor mounted in the casing, means operatively associated with the rotor for drawing a fluid substance into 40 the casing through one of said ports and the associated clamping element and for discharging it through the other port and clamping element, a cylindrical extension on the rotor projecting through an end of the 45 casing, a gear on said projection, and power means operatively connected with said gear for rotating the rotor in the cylinder.

2. In a spinning pump, the combination with a casing having a cylindrical chamber, 50 and intake and discharge ports communicating therewith, means operative in the chamber to draw a fluid substance through said intake port and to eject it through said discharge port, and means for pivotally 55 mounting the casing on an axis transverse to the longitudinal axis of said chamber whereby said pivotal axis is eccentrically arranged with respect to said cylindrical chamber.

3. In a pump, the combination with a 60 casing having intake and discharge ports and a cylindrical chamber, of means including a rotor in said chamber for drawing a fluid material into the casing through the 65 intake port and ejecting it through the dis-

charge port, and means for pivotally mounting the casing on an axis transverse to and laterally offset from the axis of said rotor.

4. In a pump, the combination with a 70 casing having a cylindrical chamber and intake and discharge ports communicating with said chamber, of means including a rotor mounted in said chamber for drawing a fluid into the casing through one port and discharging it through the other, a spiral 75 gear operatively associated with the rotor on the outside of said casing and adapted to be connected to an external source of power and means for mounting the casing on a pivotal axis extending at right angles to 80 and offset laterally from the axis of rotation of said rotor.

5. In a spinning pump, the combination with a casing having in opposite sides intake and discharge ports and a cylindrical 85 chamber with which the ports communicate, of means including a rotor in said chamber for drawing a fluid material into the casing through the intake port and ejecting it through the discharge port, said casing being adapted for pivotal mounting between clamping elements engaging the casing respectively at said ports, and said ports being arranged on a line transverse to and laterally offset from the axis of rotation of 90 said rotor so that the pressure between the clamping elements is applied to the casing eccentrically with respect to the cylindrical chamber.

6. In a spinning pump, the combination 100 with a casing having intake and discharge ports and a cylindrical chamber with which the ports communicate, of means including a rotor rotatably mounted in said chamber for drawing a fluid into the casing through 105 one port and discharging it through the other, a spiral gear coaxially connected with the rotor on the outside of said casing and adapted to be connected to an external source of power, and means including opposed casing-clamping elements for mounting the casing on a pivotal axis longitudinally transverse to the axis of rotation of 110 said rotor, and said elements engaging the casing on a line offset laterally from and transverse to said rotational axis whereby clamping pressure between the elements is applied to the casing eccentrically with respect to said chamber.

7. In a spinning pump, the combination 115 with a casing having a cylindrical chamber and intake and discharge ports communicating with said chamber, said ports being arranged in opposite sides of the casing on 120 a line transverse to and offset laterally from the longitudinal axis of said chamber, of means including a rotor mounted in the said chamber for drawing a fluid into the casing through one port and discharging it 125 through the other, a spiral gear connected 130

coaxially with the rotor at one end and externally of the casing, and means including opposed clamping elements respectively engaging the casing at the said ports for pivotally mounting the casing.

8. In a spinning pump, the combination with a casing having a cylindrical chamber and intake and discharge ports communicating with said chamber, said ports being so arranged as to adapt the pump for pivotal mounting on clamping elements engaging the casing at said ports respectively,

of means operative within the chamber for drawing a fluid material into the casing through the intake port and ejecting it 15 through the discharge port, and a solid abutment on said casing extending between the said ports and capable of withstanding pressure applied to the casing by the said clamping elements to prevent distortion of 20 the casing affecting the normal operation of the parts within the said chamber.

CHARLES W. LAWSER.
